UNITED STATES PATENT OFFICE

IRVINE JAMES ADAIR, OF DALLAS, TEXAS, ASSIGNOR OF ONE-HALF TO
EDWARD J. GANNON, OF SAME PLACE.

COPY-HOLDER.

SPECIFICATION forming part of Letters Patent No. 367,574, dated August 2, 1887.

Application filed April 28, 1887. Serial No. 236,505. (No model.)

To all whom it may concern:

Be it known that I, IRVINE JAMES ADAIR, of Dallas, in the county of Dallas and State of Texas, have invented a new and useful Improvement in Copy-Holders, of which the following is a specification.

My invention is an improved copy-holder intended especially for holding deeds when being transcribed to the records, and seeks to provide a simple inexpensive construction by which the deed may be held and to and from which the deed or other paper may be adjusted without difficulty, such construction serving also to mark or indicate the particular line of the paper being copied.

The invention consists in certain features of construction and novel combinations of parts, as will be described and claimed.

In the drawings, Figure 1 is a perspective, and Fig. 2 a sectional view of my invention.

The base A may be slotted at *a* from one edge to receive an extension-board, B, when it is desired to copy from one piece of paper to another, or it may have the extension-board 25 B formed integral with it when intended to be used in such manner. It is preferred, however, to form it with such slot, as in practice, when copying into record or other books, portions of the covers of such books may be fitted 30 into said slot, and so serve to steady the device in position. Near its edge opposite slot *a* the base has uprights C C mounted on it, and preferably inclined rearwardly from their lower to their upper ends.

35 To the uprights near their upper ends I journal the feed-rollers D D, one of which has a thumb-head or other suitable handle by which it may be turned, and the peripheries of said rollers touch and are covered with 40 rubber or similar material, so the turning thereof will operate to feed paper placed between them. These rollers are preferred; but manifestly they might be substituted by other well-known feeding devices, or they might be omitted and the paper fed forward by hand as 45 the copying proceeded.

Between the uprights and below the feed-rollers I arrange the guide-bars E F, the lower

edge of the former extending slightly below the upper edge of the latter, as shown.

The spring bail-clamp G has its arms *g* secured to the uprights and its cross-bar *g'* arranged to have a tension downward toward and against the base or against papers placed between it and said base. The arrangement 55 of the paper when being copied is shown clearly in Fig. 2, it being passed from the rear between the guide-bars E F, thence up in front of bar E, and through between rollers D D.

It will be noticed that the device holds the 60 paper to be copied in the best possible position, almost the same as one would hold a book in reading. The device also enables one to copy from the first to the last line with the instrument being copied the same distance 65 from the eye. The spring serves to hold the leaf in place when used in copying into a record-book; and when the device is used to copy from one piece of paper to another the spring serves to hold the paper on which the user is 7 writing.

Having thus described my invention, what I claim is—

1. A copy-holder having its base formed with a slot opening out of one edge and formed 75 in approximately the plane of said base, substantially as set forth.

2. The combination, in a copy-holder, of the base, the uprights, the guide-bars E F, and the clamp G, for securing the paper on which 80 the user is writing, substantially as set forth.

3. The combination, in a copy-holder, of the base, the uprights, the guide-bar E, a feeder, and a clamp, G, for securing the paper on which the user is writing, all substantially as 85 set forth.

4. The improved copy-holder herein described, consisting of the base A, having slot *a*, the uprights C C, the guide-bars E F, the feed-rollers D D, and the clamp G, all being 90 substantially as and for the purposes specified.

IRVINE JAMES ADAIR.
